GLAZER'S TOOL

Pliny L. Ullom, Sweetwater, Tex.

Application December 30, 1957, Serial No. 49,063

Term of patent 14 years

(Cl. D54—13)

Fig. 1

Fig. 2

Fig. 3

Fig. 4

Fig. 5

Figure 1 is a top plan view of a glazer's tool showing my new design;

Figure 2 is an end elevation of the glazer's tool;

Figure 3 is a side elevation of the glazer's tool;

Figure 4 is an end view opposite the end shown in Figure 2; and

Figure 5 is a bottom view of the glazer's tool.

I claim:

The ornamental design for a glazer's tool, substantially as shown.
